UNITED STATES PATENT OFFICE.

ALBERT PARK SHAW, OF PITTSFIELD, MASSACHUSETTS, ASSIGNOR TO PITTSFIELD SPARK COIL COMPANY, OF PITTSFIELD, MASSACHUSETTS, A CORPORATION OF MASSACHUSETTS.

SPARK-PLUG.

1,290,372.

Specification of Letters Patent. Patented Jan. 7, 1919.

Application filed July 9, 1917. Serial No. 179,346.

To all whom it may concern:

Be it known that I, ALBERT PARK SHAW, a citizen of the United States of America, residing in the city of Pittsfield, county of Berkshire, and State of Massachusetts, have invented certain new and useful Improvements in Spark-Plugs, of which the following is a specification.

This invention relates to improvements in spark plugs for the purpose of igniting the vaporous charge of gasolene or other inflammable substances, in an internal combustion engine, when an electric current is passed through the plug in the usual manner.

An object of the invention is to provide a spark plug that is especially adapted for use in internal combustion engines which are subject to hard service conditions as for propelling aeroplanes, or, as they are sometimes spoken of aero-motors. In this class of motors it is very necessary to provide a plug that is thoroughly reliable in every way and particularly as to breakage and one that will not fail to ignite the charge when the electric current is passed therethrough at the proper time in the cycle of operation of the motor. The present invention comprises, therefore, a plug that is composed of a substance that will not readily break, as mica, and one that is so constructed that it will not become overheated, as by forming the shell portion of the plug with fins thereon for readily radiating the heat.

Broadly, the invention comprises a core that is built up of disks or washers of different diameters, whereby shouldered portions between the disks are provided which will readily permit the formation of gas tight joints by placing suitable gaskets thereon. A recessed chamber is also provided in the lower part of the body portion of the shell and having therein a bridge or baffle member formed with perforation and through the center of this member is formed an opening to receive one of the terminals or electrodes of the plug.

The invention further comprises means for radiating the heat from the shell portion of the plug. One form of the invention having two sets of heat radiating fins, one being located at the lower part of the shell and the other at the upper end of the core member. The invention further comprises means for accurately locating the center ter-

55 minal or electrode and at the same time forming gas-tight joints between the core and shell.

Referring to the drawings:

Figure 1 shows a sectional view through the axis of the core, the core part being 60 shown in full lines, the sectional part shows the heat radiating fins, the perforated bridge and the chamber above the bridge;

Fig. 2 is a slight modification showing a 65 different method of sealing the plug in which the check nut is omitted; and

Fig. 3 is a detail sectional view of a spark plug showing the construction of the core member of the form shown in Fig. 1.

Referring to the drawings in detail, the 70 casing of the cylinder of the engine is indicated at 1, showing the inner end of the shell projecting slightly beyond the inner surface 2 thereof, as indicated at 3, the usual threads 75 for securing the plug in place in the casing being indicated at 4. The casing or shell proper of the plug is indicated at 5 and is formed with a bridge portion 6 having perforations or openings 7 extending therethrough and a centrally arranged opening 8 80 therein through which projects the usual centrally located spark terminal 9 of the plug, the other terminal 10 being secured to the casing 5 by swaging or other methods. 85

11 indicates a shouldered portion of the casing 5 with which engages a copper gasket 12. Located above the gasket 12 is a fiber or 90 mica disk 13 built up of mica washers, and located above the disk 13 is a second gasket preferably of copper and asbestos, indicated at 14. 15 is a check nut which is formed with threads 16 on its outer surface that engage threads 17 of the shell 5. When the check nut is turned downward into the shell 5 it will clamp the copper and asbestos gaskets 12 and 14 rigidly in place in the shell. 95 The check nut 15, it is to be understood, loosely surrounds the core 18 which is preferably built up of disks of mica of different diameters. The lower end of the core is also 100 preferably formed from disks of mica, as indicated at 19, but is of smaller diameter than the portion indicated at 18. The upper end of the core 18 is provided with a metallic washer 20 having a threaded hub portion 20', and above this washer is located a radiating fin 21 which is, as shown, formed as a 105 part of the cap 22 which cap as shown, is

threaded onto the stem 25, to which the electric cable which carries the spark current is connected.

Located above the bridge 6 is an air space 5 or chamber 23 that communicates with the lower part 24 of the shell by means of the openings 7 and 8, already referred to. It will be seen from this construction that any hot gases would be prevented from accumulating in the space 23, as they can readily escape through the openings 7 and 8 into the interior of the combustion chamber. The baffle plate 6 serves the further purpose of preventing the oil in the cylinder from 10 reaching or coming into direct contact with the mica core 19. Arranged below the part 19 of the core is the lower end portion 25 of the electric conducting rod 25' which conveys the spark current from the terminal 15 22 to the terminal 9 which is swaged into the lower end of the rod 25' at 25² as shown. The portion 26 may be considered the ferrule portion of the rod 25'. The upper end 20 of the rod or stem 25' is threaded as shown 25 at 25³ which receives the threaded portion 20' of the washer 20, and the threaded portion of the cap piece 22, whereby when the washer and cap piece are threaded onto the rod 25' the ferrule portion 26 will be drawn 30 upward tightly against the lower end of the core 19. The core portion 18 will be rigidly clamped therefore between the part 26 and the washer 20. Fig. 3 shows the core 35 portion 18 as made up of tubular pieces of insulating material, the tube 18' being located within the outer one, as shown. It is to be understood, however, that the core of insulating material may, and preferably is, built up of washers of insulating material, 40 preferably mica, as represented in Fig. 1 by the lines 18'.

Referring to the construction shown in Fig. 2 the shell 5 is formed with the bridge piece 6, the openings 7 and 8 and the air 45 chamber 23 above the bridge piece as already described. In this construction the check nut 15 is omitted and the enlarged part 13 of the core is retained in place by means of the bent over part 30. The parts 50 12, 13, and 14, as in the construction just referred to are located in the recessed portion of the shell and gaskets 28 and 29 are located above the upper and lower ends of the parts 12 and 14 of the core. These are 55 held in place by rolling or spinning in the metal as shown at 30 referred to above. This method forms a gas tight joint without the use of a check nut. The gaskets 28 and 29, together with the enlarged portion of the 60 core serve to center the terminal 9 in the opening 8, whereby the distance between the spark terminals will always be the same and thus insure perfect operation of the spark.

It should be stated that an important feature of my invention is the formation of the

core of the spark plug from washers of mica, or other suitable insulating material, of different diameters. Such a formation very materially lessens the cost of manufacture as it avoids accurate machining of the core to size after the assembly of the washers. This also makes possible a very compact design particularly in connection with the use of a baffle plate as described. The enlarged portion 13 of the core accurately fits the enlarged bored-out portion of the shell and, therefore, serves to accurately position the spark terminal 9 with relation to the other terminal 10. The check nut 15 further serves to accurately position the core of the plug within the casing. The fins 31 serve to maintain the casing 5 in a cool condition. The additional fin 21 also serves to conduct the heat away from the upper part of the stem or rod 25'.

The part 18' of the cone is shown as comprising a tube of insulating material, whereas the part 18 of the core is formed from disks of mica.

The spark terminals 9 and 10, it will be observed, are located in the combustion chamber of the cylinder. The bridge portion 6 not only prevents the engine from throwing oil on the insulating material but also furnishes means of locating the sparking points in the explosion chamber of the engine, or, on the cylinder side of such bridge portion.

The spark plug herein described also has the advantage of what might be termed a closed end plug. Such a construction permits the location of the sparking terminals directly within the firing or combustion chamber of the motor.

It will be observed that in Fig. 1 the nut 15 directly engages the upper side of the shouldered portion of the core and the lower side of the shouldered portion of the core directly engages the annular shouldered portion of the shell. No gaskets of any kind are employed as the mica itself forms a perfect gas tight joint.

What I claim is:

1. In a spark plug the combination of a one-piece shell having its lower end recessed, a perforated bridge spaced away from the end of shell and located in the recessed portion and formed integral with the shell, a shouldered portion on the shell above the recessed portion, a built up core consisting of tubular members formed from disks of insulating material of different diameters, the part of the core of greatest diameter engaging the shoulder portion of the shell, a check nut mounted on the core of insulating material for forcing the same into the shell for forming a gas tight joint between the core and the shell, a conducting rod extending through the core, and an electric terminal extending from the rod through the per-

forated bridge to coöperate with the other spark terminal, and for centering the core, as described.

2. A spark plug comprising, in combination, of a shell, the outer surface of which is formed with heat radiating fins, a core of insulating material located in the shell and formed from disks of insulating material, as mica, said core being of different diameter to form shoulders, a shouldered portion on the shell, a check-nut engaging the shoulders of the core to force the same against the shouldered portion of the shell and for centering the core, as described, an electric conductor passing through the core, the upper end of the conductor having a heat radiating fin, means comprising an integral perforated bridge in the lower portion of the shell above the spark terminal to permit the escape of the hot gases formed in and about the terminals of the plug and for preventing the oil in the cylinders from reaching the insulating material composing the core and which extends below the shoulder of the shell, and also for preventing pre-ignition of the charge.

3. In a spark plug, the combination with an inclosing one-piece shell, an integral baffle plate with curved surfaces near the lower end thereof for dividing the said portion of the shell into two compartments, a two-part core located in the shell, one part being formed from disks of insulating material of different diameters, a tube within the part of the core composed of disks, a portion of the core between its lower and upper ends being of greater diameter than the main body of the core, and designed to center the core in the shell, shoulders on the shell, and means comprising gaskets located above and below the last mentioned portion of the core having the greater diameter for forming gas tight joints between the core and the shell and means comprising a check nut for securing the core in place.

4. A spark plug comprising in combination with a one-piece shell formed with heat radiating fins on its outer surface, of a core located within the shell, a stem passing through the core, a portion of the core being of a diameter equal to the greatest internal diameter of the shell, gaskets engaging this portion of the core, a check nut on the core threaded into the shell and engaging a gasket to center the core and for forming a gas-tight joint between the shell and core, the lower portion of the shell having an integral perforated bridge therein to prevent the pocketing of hot gases about the lower portion of the core, as described.

5. A spark plug comprising an outer one-piece shell or body portion, a core within formed from disks of insulating material,

a portion of the core being in one piece and tubular in form, the core having a stem extending therethrough, its upper end being threaded to receive a threaded washer and a threaded cap-piece, the thread of the stem passing through both the washer and cap-piece, said cap-piece having a heat radiating fin, the lower end of the core being spaced from the inner surface of the shell, an integral baffle plate to separate the end of the core from the interior of the engine cylinder, means to secure the core in the casing and for forming a gas tight joint between the core and casing.

6. A core construction for spark plugs formed from insulating material and of different diameters, means for centering the same in a shell comprising engaging shouldered portions on the core and shell, means for forcing the shouldered portions together, said shell having a perforated baffle-plate for separating the end of the core from the interior of the engine cylinder casing for the purpose described, a spark terminal on the core extending through the baffle plate, means for clamping the insulating material together, heat radiating fins on the core and casing, and spark terminals on the core and casing.

7. A spark plug comprising an outer shell or body portion, a composite core therein composed of tubular members, one of said members being composed of washers of insulating material of different diameters, the lower end of the shell having a perforated bridge portion to protect the core from oil in the engine cylinder, said shell having its lower end located within the firing or combustion chamber of the motor, as described, a current conducting rod extending through the core and spark terminals on the shell and rod, the terminal on the rod extending through the bridge portion, and means to secure the core in the shell, said shell and conducting rod having heat radiating fins or projections.

8. A spark plug comprising in combination, a shell or body portion, a core therein, the shell having a perforated bridge or partition at its lower end to serve as a closed end for the shell of the plug to protect the core from oil, a shoulder on the shell and core, a nut loosely mounted on the core and threaded into the shell for engaging the core to secure the same in the shell and for locating the center terminal, as described, a conducting stem passing through the core, a spark terminal secured to the conducting stem and extending through a perforation in the bridge, the other terminal being on the shell, and means to secure the stem in place.

ALBERT PARK SHAW.
